US00D455715S

(12) **United States Design Patent** (10) Patent No.: **US D455,715 S**
Sakai et al. (45) Date of Patent: ** Apr. 16, 2002

(54) **BOBBIN FOR TRANSFORMER FOR ELECTRONIC DEVICE**

(75) Inventors: **Shinichi Sakai, Nara; Kazuho Sakamoto, Kyoto, both of (JP)**

(73) Assignee: **Matsushita Electric Industrial Co., Ltd., Osaka (JP)**

(**) Term: **14 Years**

(21) Appl. No.: **29/123,740**

(22) Filed: **May 24, 2000**

(30) **Foreign Application Priority Data**

Nov. 29, 1999 (JP) 11-32934

(51) LOC (7) Cl. **13-02**

(52) U.S. Cl. **D13/118**

(58) Field of Search D13/118; 336/83, 336/192, 198, 208

(57) **CLAIM**

The ornamental design for a bobbin for transformer for electronic device, as shown and described.

DESCRIPTION

FIG. 1 is a perspective view of the top, front and right side of a bobbin for transformer for electronic device showing our new design;

FIG. 2 is a front view thereof;

FIG. 3 is a rear view thereof;

FIG. 4 is a top plan view thereof;

FIG. 5 is a bottom view thereof;

FIG. 6 is a right side view thereof; and,

FIG. 7 is a left side view thereof.
